UNITED STATES PATENT OFFICE

102,433

DESIGN FOR AN ASHTRAY

Alvin Robert Lawrence, Indianapolis, Ind.

Application September 12, 1936, Serial No. 64,828

Term of patent 3½ years

To all whom it may concern:

Be it known that I, Alvin Robert Lawrence, a citizen of the United States, residing at Indianapolis, in the county of Marion and State of Indiana, have invented a new, original, and ornamental Design for Ashtrays, of which the following is a specification, reference being had to the accompanying drawing, forming part thereof.

I claim:

The ornamental design for an ashtray as shown.

A. ROBERT LAWRENCE.
